ASH FEED CONTROL

Edgar B. Tolman, Winnetka, Ill., assignor to United Conveyor Corporation, a corporation of Illinois

Filed Apr. 16, 1958, Ser. No. 728,990

9 Claims. (Cl. 302—52)

This invention relates to apparatus for feeding ash from a furnace to a storage bin, and in particular it relates to mechanism for controlling the rate of flow of ash into a vacuum or other pneumatic conveyor system.

Ash from high efficiency coal furnaces of the type used in electric power generating plants is extremely fine, and presents special problems in handling and disposition. A modern electric generating plant produces several tons of ash per hour, and this is conveniently handled in vacuum conveyor systems. Because the ash is extremely fine, it is quite difficult to handle due to arching, slumping of large masses of ash into the conveyor conduit, and other phenomena which produce uneven flow through the vacuum system and into a storage bin.

The ash handling system for a high capacity electric power plant commonly has several hoppers which receive ash from each furnace, and these hoppers act as temporary receptacles from which the ash is fed into the vacuum conveyor conduit for transmission to the storage bin. Conveniently, the system is arranged to handle ash from one boiler, or furnace, until all of the hoppers serving that furnace are exhausted; after which the system is switched so that ash is fed from the hoppers serving another furnace. The present system provides relatively even flow of ash from all of the hoppers serving a single furnace so as to minimize clogging of the vacuum conveyor conduit, and also permits all the associated hoppers to remain in communication with the vacuum conduit even though one hopper may empty sooner than another. This, of course, simplifies the control mechanism by making it unnecessary to close off the discharge opening of an empty hopper while the associated hoppers are still discharging. A group of associated hoppers may be put into the ash discharging cycle at the same time, and the control mechanism need not provide for segregating one or more hoppers of the group while the others are feeding. Feed of ash from the entire group of hoppers is terminated at one time, and the system may then be switched to another group of hoppers serving another furnace.

The operation of a vacuum conveyor system requires that the rate of flow of ash into the vacuum conduit remain fairly uniform. A certain negative pressure is required in the vacuum conduit merely to overcome the internal resistance of the system. The vacuum, of course, must be increased to overcome the added resistance to flow which results from introducing ash into the conduit. Accordingly, a system which has an air exhauster adapted to produce a particular negative pressure in the system will clog if a large quantity of ash suddenly enters the conduit. As long as the ash load remains constant at the optimum for the particular conveyor system, the vacuum remains constant. If excess material enters the conduit, the flow of air through the system is inhibited, and this increases the negative pressure in the conduit between the air exhauster and the excess load of ash. Conversely, if the volume of ash entering the

conveyor conduit is reduced, the vacuum ahead of the air exhauster becomes less. This fact is utilized in the present system to control the feed of ash into the conduit by means of suitable vacuum controlled valves.

- 5 Each hopper in the present system is provided with an ash feed opening, and associated with the ash feed opening is a conventional mechanism for fluidizing the ash so that it flows readily through the opening. The feed of ash is not controlled by opening and closing the feed openings, but instead is controlled by starting and stopping the flow of fluidizing air to the fluidizing units associated with the feed openings. The vacuum controlled valves admit fluidizing air until such time as an increase in the vacuum of the system results from 15 excessive ash in the conduit; and this increase in vacuum is utilized to suspend the aerating air until the vacuum in the system again decreases to the point where the system can handle additional ash, at which point the flow of aerating air is resumed.
- 20 The present disclosure deals only with pressures which are below atmospheric, so in the specification and claims the word "minimum" is used to refer to a pressure nearest to atmospheric, while "maximum" refers to a pressure farther from atmospheric. "Intermediate" refers 25 to a pressure between maximum and minimum, "reduction of vacuum" means that the vacuum system approaches atmospheric pressure.

The invention is illustrated diagrammatically in the accompanying drawing, which illustrates the control for 30 two hoppers which feed into the vacuum conduit simultaneously. When the two illustrated hoppers are empty, they are segregated from the conduit and a similar group of hoppers (not illustrated) is placed in communication with the conduit under a similar control system.

35 Referring to the drawing in greater detail, the system includes hoppers, indicated generally at 1 and 2, which are provided respectively, with outfeed mechanisms, indicated generally at 3 and 4. Each hopper is the bottom portion of a centrifugal or electrostatic separator of conventional design, which separates ash from the hot air coming out of a furnace. Outfeed mechanisms 3 and 4 have discharge pipes 5 and 6, respectively, which are connected to a vacuum conduit 7; and the conduit 7 feeds through a conventional centrifugal separator 8 where the ash is removed from the conveying air stream for deposit in a storage bin 9. From the separator 8, the air passes through a suction conduit 10; and air flow through the system is provided by conventional fluid 45 operated air exhauster, indicated generally at 11.

50 The flow of ash into the conduit 7 from the feed mechanisms 3 and 4 is controlled by a vacuum system indicated generally at 12, which includes a vacuum control pipe 13 connected to the vacuum conduit 10.

The two ash hoppers and their associated ash feed 55 mechanisms are identical, so only the hopper 1 and the feed mechanisms 3 are described in detail. Each hopper has a continuous upright side wall 14 which is the lower part of a separator, and which merges into a frusto-pyramidal bottom 15 provided with a discharge throat 16 through which ash enters the feed mechanism 3.

In the bottom portion 15 of the hopper is an arrangement of fluidizing stones 17 which are spaced apart to afford a passage 18 through which ash flows to the throat 16. The hopper construction here disclosed is disclosed and 60 claimed in my copending application, S.N. 728,989, filed April 16, 1958.

The ash feed mechanism 3 consists of a chamber 19 having an inclined fluidizing stone 20, and a feed opening 21 in one wall of the chamber 19 has its lower margin flush with the surface of the fluidizing stone 20 so that fluidized ash in the chamber 19 may flow through the pipe

5 and into the conduit 7. The feed mechanism 3 also includes a cutoff valve 22 to close the opening 21 when the feed of ash from the hoppers 1 and 2 terminates; and the valve 22 is operated by a conventional air cylinder 23.

Low pressure air for the fluidizing stones 17 and 20 comes through a supply pipe 24 which serves both the hopper 1 and the hopper 2, there being a branch line 25 for the fluidizing stones 17 in the hopper 1, a branch line 26 for the fluidizing stone 20 in the feed mechanism 3, and similar branch lines 27 and 28 for the corresponding parts of the hopper 2 and feed mechanism 4.

Flow of fluidizing air to the branch lines 25 to 28, inclusive, is controlled by a solenoid valve 29, which in turn is opened and closed by a vacuum switch 30 in the vacuum control pipe 13. When the system is first started, there must be a minimum vacuum within the conduit 7 before any ash is fed out of the hoppers. Accordingly, the vacuum switch 30 is set to open the solenoid valve 29 at a predetermined minimum pressure which is suitable for the particular installation. This admits low pressure air from the supply line 24 to the fluidizing stones 17 and 20 and so fluidizes, or aerates, the ash in the lower portions of the hoppers and the associated feed mechanisms that the ash may flow freely through the feed openings 21 into the conduit 7. As the ash load in conduit 7 increases, the pressure in the vacuum control pipe 13 approaches the maximum which can be properly utilized with the particular air exhauster 11 in the system. In a typical system the maximum negative pressure might be 18 inches Hg, or greater in certain types of systems. If the rate of flow of ash into the conduit 7 is heavy enough to bring the negative pressure in the vacuum control pipe 13 above the optimum of 18 inches Hg, the pressure acts upon the vacuum switch 30 to close the solenoid valve 29 and thus suspend the flow of aerating air to the stones 17 and 20. Flow of ash into conduit 7 is thereby suspended and the pressure in the control pipe 13 approaches an intermediate pressure at which efficient operation of the system requires that the flow of ash be resumed. When the intermediate pressure is reached, valve 29 again opens. The pressure difference between the suspension of flow and resumption of flow may be 3 or 4 inches Hg. Thus fluidizer 20 constitutes flow control means positioned between hopper 1 and conduit 7 to control the movement of ash from the hopper to the conduit and varies rapidly between a first condition which permits no movement of ash into the conduit and a second condition which permits maximum movement of ash into the conduit.

A great advantage of the present system is that it permits the use of feed openings 21 from the feed mechanisms which are small enough that the valve 22 need not be closed if the hopper 1 is empty and the hopper 2 is still feeding. The ash flow is controlled entirely by fluidizing it, and the valves 22 are closed only when all the hoppers of a group are emptied. The system is illustrated with only 2 hoppers in a group, but a typical large capacity installation might have four or six hoppers in a single group rather than two. The air which might be drawn into the vacuum conduit 7 through an empty hopper is small enough in volume that it does not interfere materially with the conveying of ash entering the conduit from the hoppers which are not yet emptied.

The foregoing detailed description is given for clearness of understanding only and no unnecessary limitations should be understood therefrom, as modifications will be obvious to those skilled in the art.

I claim:

1. Apparatus for feeding ash at a controlled rate comprising: a plurality of ash receiving hoppers; a vacuum conveyor system; a plurality of outfeed mechanisms, there being one such mechanism in communication between each of said hoppers and said vacuum system, each outfeed mechanism including an aerating chamber having a

5 feed opening of sufficiently small area in proportion to the area of all of said openings that the reduction of vacuum in said conduit resulting from the free flow of air through a hopper produces only a small reduction in the ash moving characteristics of the apparatus; aerating means for 10 simultaneously aerating the ash in all said chambers; a solenoid valve for controlling said air supply; and a vacuum controlled electric switch in said vacuum system for operating said valve in accordance with predetermined 15 pressures in said system, whereby the aerating means operates to facilitate flow of ash from the hoppers to the conveyor system when the pressure in said system is within a predetermined range.

2. Apparatus for feeding ash at a controlled rate, comprising: a plurality of ash receiving hoppers; a vacuum conveyor conduit; an outfeed mechanism for each hopper, each said mechanism including an aerating chamber having a constantly open feed opening through which ash passes from the hopper to said conduit, the area of each 20 opening being sufficiently small in proportion to the total area of all said openings that the reduction of vacuum in said conduit resulting from free flow of air through a hopper produces only a small reduction in the ash moving characteristics of the apparatus; means for aerating 25 ash in each of said chambers to facilitate the flow of ash from said hoppers to said conduit; and means controlled by the amount of ash in said conduit for selectively actuating said aerating means.

3. Apparatus for feeding ash at a controlled rate, comprising: a vacuum conveyor conduit; vacuum means for drawing air through said conduit to move a predetermined volume of ash per unit time; dust collector means to receive ash moved through said conduit; a plurality of ash receiving hoppers; a separate aerating chamber in 35 direct communication with each of said hoppers, each said aerating chamber having an outlet orifice in communication with said conduit, the area of a single orifice being so small in proportion to the total area of all said orifices that the reduction of vacuum in said conduit resulting from free flow of air through a hopper produces only a small reduction in the ash moving characteristics of the apparatus; means for aerating the ash in all said 40 aerating chambers; and control means to limit the operation of said aerating means in accordance with the level of 45 vacuum in the conduit.

4. Apparatus for feeding ash at a controlled rate, comprising: a vacuum conveyor conduit; vacuum means for drawing air through said conduit to move a predetermined volume of ash per unit time; dust collector means to receive ash moved through said conduit; a plurality of ash receiving hoppers; a separate aerating chamber in direct 50 communication with each of said hoppers, each said aerating chamber having an outlet orifice in communication with said conduit, the area of a single orifice being so small in proportion to the total area of all said orifices that the reduction of vacuum in said conduit resulting from exhaustion of the ash from any one hopper produces only a small reduction in the ash moving characteristics of the apparatus; means for aerating the ash in all said 55 aerating chambers; a valve controlling the flow of air to said aerating means; and vacuum operated control means for said valve in communication with said vacuum conveyor system to open and close said valve when the conduit is under vacuum, said control means being constructed and arranged to stop the flow of aerating air when the pressure in the system reaches a predetermined maximum, and to resume the flow of said aerating air when said pressure reaches a predetermined intermediate level.

5. Apparatus for feeding ash at a controlled rate, comprising: an ash receiving hopper; an ash outfeed mechanism connected with the bottom of said hopper, said outfeed mechanism including an aerating chamber having a feed opening of restricted size in a side wall; aerating 60 means for aerating the ash in said chamber; a valve con-

75 nected with the side wall of said chamber; and a valve

trolling the flow of air to said aerating means, said valve being of a type which has only a fully open and a fully closed position; a vacuum conveyor system to transport ash discharged through said feed opening, said system including a dust collector and means for discharging ash from said collector to a storage bin; means for producing a negative pressure in said vacuum system; starting means for fully opening said valve when the negative pressure in the system reaches a predetermined minimum; and control means which responds to variations in the negative pressure in said vacuum system to fully open and fully close said valve while the conveyor system is under vacuum, said control means being constructed and arranged to fully close said valve when the negative pressure in the system reaches a predetermined maximum, and to fully reopen said valve when said pressure reaches a predetermined intermediate level between said minimum and maximum pressures.

6. Apparatus for feeding ash at a controlled rate, comprising: an ash receiving hopper; a pneumatic conveyor conduit; air moving means for producing in said conduit an air pressure different from atmospheric pressure; flow control means positioned between said hopper and said conduit to control the flow of ash from the hopper to the conduit, said flow control means including a chamber having a feed opening of restricted size in a side wall, said chamber being provided with aerating means to fluidize material for free flow through the opening, and a movable valve for selectively closing said opening, and said flow control means varying rapidly between a first condition permitting no flow of ash and a second condition permitting maximum flow of ash through said opening; and control means which responds to the pressure in the conveyor conduit to control said flow control means by varying it between said first and second conditions, said control means being constructed and arranged to place said flow control means in said second condition when pressure in the conduit reaches a first level close to atmospheric pressure at which flow of ash into the conduit is desired, to return said flow control means to said first condition when excessive ash in the conduit causes pressure to reach a second level a maximum distance from atmospheric pressure, and thereafter to restore said flow control means to said second condition when reduction of the quantity of ash in the conduit has caused pressure in the conduit to reach a predetermined intermediate level between said first and second pressures.

7. Apparatus for feeding ash at a controlled rate, comprising: an ash receiving hopper; a pneumatic conveyor conduit; air moving means for producing in said conduit an air pressure different from atmospheric pressure; flow control means positioned between said hopper and said conduit to control the flow of ash from the hopper to the conduit, said flow control means including a chamber having a feed opening of restricted size in a side wall, said chamber being provided with aerating means to fluidize material for free flow through the opening, and said flow control means varying rapidly between a first condition permitting no flow of ash and a second condition permitting maximum flow of ash; an air valve which closes to place said flow control means in said first condition and which opens to place said means in said second condition; and control means which responds to the pressure in the conveyor conduit to open and close said air valve, said control means being constructed and arranged

to completely open said air valve when pressure in the conduit reaches a first level close to atmospheric pressure at which flow of ash into the conduit is desired, to completely close said valve when excessive ash in the conduit causes pressure to reach a second level a maximum distance from atmospheric pressure, and thereafter to again completely open said valve when reduction of the quantity of ash in the conduit has caused pressure in the conduit to drop to a predetermined level between said first and second pressures.

8. Apparatus for feeding ash at a controlled rate, comprising: an ash receiving hopper; a pneumatic conveyor conduit; air moving means for producing in said conduit an air pressure different from atmospheric pressure; flow control means positioned between said hopper and said conduit to control the flow of ash from the hopper to the conduit, said flow control means including a chamber having a feed opening of restricted size in a side wall, said chamber being provided with aerating means to fluidize material for free flow through the opening, and said flow control means varying rapidly between a first condition permitting no flow of ash and a second condition permitting maximum flow of ash; starting means for placing said flow control means in said second condition when pressure in the conduit reaches a first level close to atmospheric pressure; and control means constructed and arranged to place said flow control means in said first condition when excessive ash in the conduit causes pressure to reach a second level a maximum distance from atmospheric pressure, and thereafter to restore said flow control means to said second condition when reduction of the quantity of ash in the conduit has caused pressure in the conduit to reach a predetermined intermediate level between said first and second pressures.

9. Apparatus for feeding ash at a controlled rate, comprising: an ash receiving hopper; a vacuum conveyor conduit; air moving means for producing a negative pressure in said conduit; flow control means positioned between said hopper and said conduit to control the flow of ash from the hopper to the conduit, said flow control means including a chamber having a feed opening of restricted size in a side wall, said chamber being provided with aerating means to fluidize material for free flow through the opening, and said flow control means varying rapidly between a first condition permitting no flow of ash and a second condition permitting maximum flow of ash; an air valve which closes to place said flow control means in said first condition and which opens to place said means in said second condition; starting means for opening said air valve when the negative pressure in the conduit reaches a predetermined minimum; and control means which responds to variations in the negative pressure in the conduit to open and close said valve while the conduit is under vacuum, said control means being constructed and arranged to close said valve when the negative pressure in the conduit reaches a predetermined maximum, and to reopen said valve when said pressure reaches a predetermined intermediate level between said minimum and maximum pressures.
